UNITED STATES PATENT OFFICE.

ENDFRED LUNDBERG, OF TORONTO, ONTARIO, CANADA, ASSIGNOR, BY DIRECT AND MESNE ASSIGNMENTS, OF ONE-HALF TO OTTO HIGEL COMPANY, INC., OF BUFFALO, NEW YORK, A CORPORATION OF NEW YORK, AND ONE-HALF TO GEORGE P. BRAND, OF NEW YORK, N. Y.

DUST-REMOVER FOR TRACKING DEVICES.

1,212,652.

Specification of Letters Patent. Patented Jan. 16, 1917.

Application filed August 7, 1915. Serial No. 44,138.

To all whom it may concern:

Be it known that I, ENDFRED LUNDBERG, a citizen of the United States, residing at Toronto, in the Province of Ontario, in the 5 Dominion of Canada, have invented new and useful Improvements in Dust-Removers for Tracking Devices, of which the following is a specification.

This invention relates to cleaning means 10 for the automatic tracking devices employed in player-pianos and other self-playing instruments for maintaining the music sheet in its normal central position, in order to insure proper registration between the 15 perforations of the music sheet and the tracker ducts.

The invention has more particular reference to pneumatic tracking devices or those 20 in which the music spools or the tracker are shifted, one with relation to the other, by motor pneumatics under the control of ducts or passages which in turn are controlled directly or indirectly by lateral deviations of the music sheet, in a well known 25 manner. Dust, lint and particles of paper enter these controlling ducts and the valve-box or case connected therewith, sometimes clogging them to such an extent as to interfere with the proper action of the tracking 30 devices.

One of the objects of my invention is the provision of simple and effective means by which such controlling ducts may be readily cleared of dust and other obstructions.

35 A further object is to so combine the device with the roll-driving means of the instrument that it automatically cleans such ducts whenever the usual key is shifted to re-roll the music sheet, thus always keeping 40 the ducts free and unobstructed and insuring the proper operation of the tracking mechanism at all times.

In the accompanying drawings: Figure 1 is a front elevation of a tracker box and 45 tracking device equipped with the improved dust remover or cleaning device, showing the position of the parts when the device is in operation, the main bellows of the instrument being shown on a relatively reduced scale. Figs. 2 and 3 are horizontal sections on lines 2—2 and 3—3, Fig. 1. Fig. 50 4 is an enlarged longitudinal section of the

cleaning valve on line 4—4, Fig. 2, showing the same opened to clean the controlling ducts. Fig. 5 is a transverse section on line 5—5, Fig. 4. Fig. 6 is a top plan view of the body or block of the cleaning valve. Fig. 7 is a bottom plan view of said valve. Fig. 8 is a section similar to Fig. 4, showing the valve closed to cut off the cleaning 60 device.

Similar characters of reference indicate corresponding parts throughout the several views.

1 indicates the side walls of the usual 65 tracker box and 2 the tracker which, in the example of the invention shown in the drawings, is fixed and provided with the customary row of note ducts 3 and at one or both ends of said row with one or more controlling ducts 4 adapted to be covered or uncovered by the margins of the music sheet 5 or controlled by an equivalent part or parts. The end ducts 4 control any suitable or well known mechanism by which the 70 music sheet is automatically returned to its proper tracking position the moment it tends to deviate from its true course. In the example shown in the drawings, this mechanism is of the well-known type comprising a 75 pair of oppositely-acting motor pneumatics 6 which shift the music roll 7 axially in one or the other direction.

8 and 9 indicate the tubes which lead from the controlling ducts 4 to any suitable or 80 customary valve mechanism which controls the inflation and deflation of said motor pneumatics in a well-known manner. This valve mechanism is well understood by those skilled in the art and is therefore not illustrated in the drawings. In the construction shown, it is inclosed in the box or case 10, to opposite sides of which the inner fixed boards of the motor pneumatics are secured. Their movable boards are coupled together 85 by the usual link 11.

In the example herein illustrated, the shaft 12 which drives the music roll is free to slide lengthwise in its bearing in the tracker box, the opposite end of the music 100 roll being carried by the usual spring-pressed bearing pin or stud 13. Bearing against the free end of the shaft 12 is a shifting arm 14 which is secured to an up-

right rock shaft 15 journaled in a frame 16, the latter being secured to the adjacent end of the tracker box. This rock shaft has an arm 17 connected by links 18 and 19 with the movable board of the inner motor pneumatic 6. By these connections the music roll is shifted in one or the other direction by the collapse of the motor pneumatics, in an obvious manner.

10 The mechanism for alternately driving the usual take-up roll 20 and the music roll 7 may be of any desired or well-known construction. That shown in the drawings is of the common form comprising the main driving shaft 21, constantly turning in the same direction; the chain 22 and sprockets 23 and 24 connecting the music roll shaft with said main shaft; and the driving shaft 25 of the take-up roll having the gear wheel 26 adapted to be engaged by the pinion 27 carried by the clutch collar 28. The collar is splined on the main shaft and has the usual clutch-pin or pins 29 adapted to engage similar pins 30 on the sprocket 23 which is loosely journaled on the main shaft in a well known manner. The clutch collar 28 is shifted by an arm 31 secured to a vertical rock shaft 32 carrying an actuating arm 33. The latter is connected to a horizontal slide 34 journaled in the base of the tracker box and having a finger piece or key 35 for shifting it. This roll-winding and rewinding mechanism operates in the customary manner, the music sheet being wound upon the take-up roll when the pinion 27 is moved into gear with the gear wheel 26, and the sheet being rewound upon the music roll when said pinion is withdrawn and the clutch collar 28 moved into engagement with the loose sprocket wheel 23, as shown in Fig. 1.

In its preferred embodiment illustrated in the drawings, the improved duct-cleaning device comprises a block 36 containing in its lower portion a wind or suction passage or chamber 37 connected by a tube 38 with a suitable exhaust or wind-inducing device, chamber or conduit, such as the usual main suction bellows 39 of the instrument, where- 45 by said passage is constantly exhausted so long as the main bellows is actuated. Arranged above the passage 37 is a longitudinal groove or guideway 40 the bottom of which forms a seat for a valve 41, preferably 50 of the sliding type, as shown. Extending upwardly from the passage 37 to said valve seat are ports 42 corresponding in number to the number of controlling ducts 4. Located at one side of each of these ports is a 55 similar port 43 which is connected by a branch tube 44 with the main tube 8 or 9 of one of said controlling ducts, there being a pair of such co-operating ports 42 and 43 for each controlling duct. The slide valve 60 41 is provided in its underside with trans- 65 scribed.

verse channels or ports 45, each adapted to bridge and connect a pair of the ports 42, 43 when brought into register therewith, as shown in Figs. 4 and 5. When the valve is moved into this open position the controlling ducts 4 are placed in communication with the suction passage 37, causing any dust, lint or other foreign substances lodging in them and the valve box or case connected therewith to be withdrawn through said passage into the main bellows 75 39, from which the accumulations are removed from time to time. When the valve is shifted to its closed position, as shown in Fig. 8, its ports break register with the ports 42 and 43, cutting off communication between the suction passage 37 and the controlling ports and allowing the tracker mechanism to operate in its normal manner. The valve is held down upon its seat by a spring 46 or other suitable means. This flushing or cleaning device may be operated by hand, if desired, but it is preferably combined with the roll-driving mechanism in such a manner that the cleaning valve is 80 automatically moved to its open or operative position in the act of shifting the key 35 to rewind the music sheet. In the example shown in the drawings, this is accomplished by connecting the cleaning valve 95 41 with the key-slide 34 by a rod 47.

By this construction and arrangement, the controlling ducts 4 and connecting passages are subjected to the cleaning or flushing action of the suction current whenever a 100 music sheet is rewound. This renders it impossible to re-roll a sheet without simultaneously cleaning said ducts, thus maintaining the tracking device in proper working order at all times.

When the key 35 is shifted to take up the music sheet, the cleaning valve is at the same time closed, cutting out the cleaning device while the instrument is playing. While affording this important advantage, 110 the improvement is exceedingly simple in construction, its cost is but nominal and it can be readily applied to existing as well as new tracking devices of this kind.

In the drawings, the improvement is 115 shown as applied to a tracker having two controlling ducts, one near each edge of the music sheet, but the improvement is equally applicable to trackers having a pair of such ducts near each end thereof, or a different 120 number, the cleaning valve being provided with as many sets of ports 42, 43 and 45 as there are controlling ducts.

The construction of the device may be changed or modified within the scope of the 125 appended claims without departing from the spirit of the invention, and I do not therefore wish to be limited to the particular embodiment thereof herein shown and de- 130

I claim as my invention:

1. The combination with a tracking device for a music sheet, including shifting means for maintaining proper registration between the sheet and the tracker and a controlling duct for said shifting means, of cleaning means for said duct, comprising a wind-inducing device and means for establishing or cutting off communication between said duct and said wind-inducing device.

2. The combination with a tracking device for a music sheet, including shifting means for maintaining proper registration between the sheet and the tracker and a controlling duct for said shifting means, of cleaning means for said duct, comprising a suction device, and a valve-controlled connection between said suction device and said controlling duct.

3. The combination of a tracker, music and take-up rolls, mechanism for alternately driving said rolls to wind a sheet upon the take-up roll and rewind it upon the music roll, controlling means for said driving mechanism, a tracking device for the music sheet including shifting means for maintaining proper registration between the sheet and the tracker and a controlling duct for said shifting means, and a pneumatic cleaning device connected with said duct and controlled by said controlling means.

4. The combination of a tracker, music and take-up rolls, mechanism for alternately driving said rolls to wind a sheet upon the take-up roll and rewind it upon the music roll, controlling means for said driving mechanism, a tracking device for the music sheet including shifting means for maintaining proper registration between the sheet and the tracker and a controlling duct for said shifting means, and a suction device connected with said duct and controlled by said controlling means.

5. The combination of a tracker, music and take-up rolls, mechanism for alternately driving said rolls to wind a sheet upon the take-up roll and rewind it upon the music roll, controlling means for said driving mechanism, a tracking device for the music sheet including shifting means for maintaining proper registration between the sheet and the tracker and a controlling duct for said shifting means, a suction chamber, a connection between said chamber and said duct, and a valve controlling said connection and operatively connected with said controlling means to establish communication between said duct and said chamber when the driving mechanism is shifted to rewind the music sheet.

6. The combination with a tracking device for a music sheet, including shifting

means for maintaining proper registration between the sheet and the tracker, a controlling-duct for said shifting means and a main tracker tube leading from said duct to said shifting means, of a suction device, a branch-tube leading from said suction device to said main tube, and a valve controlling communication between said suction device and said branch-tube.

7. The combination with a tracking device for a music sheet, including shifting means for maintaining proper registration between the sheet and the tracker and a controlling-duct for said shifting means, of cleaning means for said duct, comprising a block having a wind-passage, a valve-seat, a pair of ports, one leading from said passage to said seat and the other communicating with said controlling duct and terminating at said seat, and a valve applied to said seat and having a channel arranged to register with and connect said pair of ports in one position of the valve and to break register with said ports in another position of the valve.

8. The combination of a tracker, music and take-up rolls, mechanism for alternately driving said rolls to wind a sheet upon the take-up roll and rewind it upon the music roll, controlling means for said driving mechanism, a tracking device for the music sheet including shifting means for maintaining proper registration between the sheet and the tracker and a controlling duct for said shifting means, a block having a wind-passage, a valve seat, a pair of ports, one leading from said passage to said seat and the other communicating with said controlling duct and terminating at said seat, and a valve applied to said seat and having a channel arranged to connect said pair of ports, and connecting means between said valve and said controlling means.

9. The combination with a tracking device for a music sheet, including shifting means for maintaining proper registration between the sheet and the tracker and a controlling-duct for said shifting means, of cleaning means for said duct comprising a block having a longitudinal suction passage, a valve seat, a pair of ports, one leading from said passage to said seat and the other connected with said controlling duct and terminating at said seat at one side of the first-named port, a slide-valve applied to said seat and having a transverse channel arranged to bridge and connect said pair of ports, and means for operating said valve.

ENDFRED LUNDBERG.
